UNITED STATES PATENT OFFICE.

GEORGE K. CUMMINGS, OF NEW YORK, N. Y.

DESIGN FOR A PRISM-WINDOW.

SPECIFICATION forming part of Design No. 29,806, dated December 13, 1898.

Application filed August 15, 1898. Serial No. 688,626. Term of patent 7 years.

To all whom it may concern:

Be it known that I, GEORGE K. CUMMINGS, a citizen of the United States, residing at New York, in the county and State of New York, 5 have invented and produced a new and useful Design for Prism-Windows, of which the following is a specification.

My invention relates to a new design for prism-windows, and is illustrated in the accompanying drawings, in which—

Figure 1 is an elevation or front view of a prism-window embodying my said design, and Fig. 2 is a vertical cross-section through the window on a line a little to the right of the 5 middle of the window, as seen in Fig. 1.

The design consists of a number of variously-shaped panes, plates, or lights of prism-glass grouped together so as to form a single window or design.

5 The parallel cross-lines of the drawings represent the angular edges of the glass prisms, which, with a body portion of glass, constitute the said panes, plates, or lights. The heavier doubled lines of the drawings represent the framework.

The design is described as follows: Within a rectangular parallelogram appear a number of substantially parallel lines having double

curves, like the letter **S**, and similar lines with reverse curves crossing them at various 30 predetermined points, said lines being the boundaries of variously-shaped prism-lights, the whole producing the effect of a barred or grated window with curved gratings, as clearly shown in the drawings.

At the bottom of the design there is a row of substantially triangular-shaped prism-lights, then a row of kite-shaped prism-lights, then a row of oval-shaped prism-lights, then a row 40 of kite-shaped prism-lights, then a row of diamond-shaped prism-lights, then a row of kite-shaped prism-lights, then a row of oval-shaped prism-lights, then a row of kite-shaped prism-lights, and at the top a row of substantially triangular-shaped prism-lights. 45

I claim—

The design for a prism-window as herein shown and described.

In testimony whereof I have signed my name to this specification in the presence of 50 two subscribing witnesses.

GEORGE K. CUMMINGS.

Witnesses:

EDWIN SEGER,
SIDNEY MANN.
